BED SPRING

Charles J. Elder, Muncie, Ind., assignor to The
Moore Company, Muncie, Ind., a corporation of
Indiana

Application September 1, 1944, Serial No. 552,283

5 Claims. (Cl. 5—247)

1

My invention relates to bed springs, and has for its object the production of a bed spring which will provide improved comfort, which will be sturdy and durable in use, and which can be simply and economically manufactured.

A bed spring embodying my invention comprises a generally rectangular base frame provided with cross members which support spring elements of novel form. Each of these spring elements comprises a piece of spring wire bent to provide an upper, horizontal stretch, end stretches each embodying at least one helical coil, and juxtaposed bottom stretches secured to the base frame. The horizontal upper stretches of the spring elements are all substantially coplanar with each other and with a border frame, and are secured to each other and to the border frame by means including flexible strips of metal and tension springs.

The accompanying drawing illustrates my invention; Fig. 1 is a fragmental top plan view of a bed spring; Fig. 2 is a section on the line 2—2 on Fig. 1; Figs. 3 and 4 are, respectively, an elevation and a plan view of one of the spring elements; and Fig. 5 is a section on the line 5—5 of Fig. 3.

The bed spring illustrated in the drawing comprises a base frame including a generally rectangular border member 10 provided with a plurality of regularly spaced cross members 11. The cross members 11, and preferably also the sides of the frame 10, support a plurality of transverse rows of spring elements each designated generally by the reference numeral 12.

The spring elements 12 are of a peculiar form perhaps best illustrated in Figs. 3 and 4. As will be clear from those figures, each of such elements is formed of wire and has an upper horizontal stretch 15, end stretches 16 each of which contains at least one helical turn 17, and juxtaposed lower stretches 18. Each of the lower stretches 18 at its free end is formed with an open eye 19 terminating in a reversely bent hook 20. The eyes 19 are formed to lie substantially in the same horizontal plane, and preferably on the same side of the element.

In the preferred method of mounting the spring elements 12 on the base frame, each of the cross members 11 includes a transversely extending strip or flange 22. At intervals, each strip 22 is provided with T-shaped notches 23, as indicated in Fig. 5. The proportions of each of these notches is such that its wider lower portion will receive at one end the two lower stretches 18 of an element 12 and at the other end the hook 20 of one of such stretches.

2

The elements 12 are desirably arranged as indicated in Figs. 1 and 2, the elements of each transverse row being staggered relative to the elements of adjacent rows and overlapping the elements of adjacent rows longitudinally of the spring. As a result, each of the inner strips or flanges 22 may support opposite ends of the spring elements 12 of adjacent rows.

The upper stretches 15 of the elements 12 are interconnected by flexible metal strips 25 extending transversely of the bed spring and overlying the upper stretches 15 of the spring elements. At the points where each strip 25 crosses one of the upper stretches 15 of a spring element it is provided with a down-struck tongue 25' bent into the form of a hook to embrace such horizontal stretch. The ends of the strips 25 are desirably connected through helical tension springs 26 to the sides of a generally rectangular border frame 27 which surrounds the assembly in the common plane of the upper stretches 15. In addition, adjacent strips 25 are desirably interconnected by helical tension springs 28. The end strip 25 adjacent each end of the border frame 27 may be connected thereto by metallic straps 29.

To oppose horizontal displacement of the border frame 27 relative to the base frame 10—11, such two frames may be interconnected by a stabilizer 30. Such stabilizers are well known, and therefore need not be described.

In assembling the bed spring, each spring element is secured to the base frame by collapsing the open end of each eye 19 and inserting the two lower stretches 18 of the element and the hook 20 on one of them through the narrow neck of a T-slot 23. Upon release of the effort employed to collapse the eye, the latter expands into the position illustrated in Fig. 4 with the hook 20 embracing the edge of the metal at one end of the slot 23 and with the two stretches 18 at the opposite end of such slot. Desirably, in mounting each of the spring elements 12 on the bottom frame the lower horizontal stretches are crossed, as will be clear from Figs. 3 and 4. This crossing provides a greater stability, prevents the stretches from bowing as a result of the reactions transmitted to them at the ends of the T-slot 23, and tends to prevent noise.

I claim as my invention:

50 1. In a bed spring, a base frame, a plurality of spring elements mounted on said base frame, each of said spring elements being formed of wire bent to provide an upper stretch and end stretches each including at least one helical turn, the upper 55 stretches of said elements being substantially co-

planar, and flexible means connecting such upper stretches with each other, said elements being arranged in parallel rows with their upper stretches extending transversely of the rows, said base frame being provided with element-supporting members extending parallel to the rows of spring elements and provided in their upper edges with alined T-shaped slots, each of said elements including two juxtaposed lower stretches extending between adjacent ones of said members and disposed in the T-slots therein, each of said lower stretches being provided at its end with an open eye disposed in a horizontal plane and terminating in a reversely bent hook, each of said hooks being disposed in a T-slot and the two lower stretches of the element crossing each other between the two adjacent supporting members.

2. In a bed spring, a base frame, a plurality of spring elements mounted on said base frame, each of said spring elements being formed of wire bent to provide an upper stretch and end stretches each including at least one helical turn, the upper stretches of said elements being substantially coplanar, and flexible means connecting such upper stretches with each other, said elements being arranged in parallel rows with their upper stretches extending transversely of the rows, said base frame being provided with element-supporting members extending parallel to the rows of spring elements and provided in their upper edges with alined T-shaped slots, each of said elements including two juxtaposed lower stretches extending between adjacent ones of said members and disposed in the T-slots therein, each of said lower stretches being provided at its end with an open eye disposed in a horizontal plane and terminating in a reversely bent hook, each of said hooks being disposed in a T-slot.

3. In a bed spring, a base frame, a plurality of spring elements mounted on said base frame, each of said spring elements being formed of wire bent to provide an upper stretch and end stretches each including at least one helical turn, the upper stretches of said elements being substantially coplanar, and flexible means connect-

ing such upper stretches with each other, each of said elements including two juxtaposed lower stretches, each of said lower stretches being provided at its end with an open eye which terminates in a reversely bent hook, said base frame including parallel element-supporting members provided in their upper edges with T-shaped slots each of which receives the two lower stretches of a spring element and the hook of one of them.

4. A spring element for incorporation in a bed spring or the like, said element being formed of wire to provide an upper stretch, two end stretches each including at least one helical turn, and juxtaposed lower stretches, said upper and lower stretches being free of reverse bends, each of said lower stretches being provided at its end with an open eye which terminates in a reversely bent hook, said upper and end stretches lying approximately in a common vertical plane, each eye and its associated hook lying in a plane substantially perpendicular to said first named plane.

5. The invention set forth in claim 4 with the addition that said eyes are offset in the same direction from the respective lower stretches.

CHARLES J. ELDER.
